RALPH E. BLACKFORD AND CHARLES BUTTERFIELD, OF MIDDLETOWN, OHIO.

METHOD OF MAKING METAL CANS.

Application filed December 22, 1924. Serial No. 757,345.

To all whom it may concern:

Be it known that we, RALPH E. BLACKFORD and CHARLES BUTTERFIELD, citizens of the United States, residing at Middletown, in the county of Butler and State of Ohio, have invented certain new and useful Improvements in the Method of Making Metal Cans, of which the following is a specification.

10 This invention relates to new and useful improvements in the method of making metal cans.

It is the principal object of our invention to provide an efficient metal can which may be economically manufactured under our improved method. While this method may be employed in the production of any type of can, it is the object of our invention to adapt it particularly to the formation of a substantially rectangular ice-can in order that the latter may be made cheaply, strong and without any kinks or warps appearing in it.

In the accompanying drawings, Figure 1 is a top plan view of the welded cylinder. Figure 2 is a side view thereof. Figure 3 is a top plan view of the substantially rectangular, finished ice-can. Figure 4 is a side view of the latter, partly in section. And Figure 5 is a bottom plan view of the can bottom, the dash lines indicating the shape of the blank before it is bent to final form and the dot and dash lines indicating the bending lines.

Our improved method of producing cans, particularly ice-cans, consists first in rolling a strip 1 of suitable metal such as steel, to substantially cylindrical form as shown in Figures 1 and 2, and then welding its free longitudinal edges together as at 2. The cylinder is then brought into the substantial shape and size desired, in this instance a rectangular one, by suitable dies, preferably internally-expanding ones, after which it is coated against the action of air, moisture and chemicals. We prefer to galvanize it for this purpose.

After the metal sheet thus formed is galvanized, the dies are reinserted and operated to take out any kinks or warps that may have developed in it during the galvanizing process. The second operation of the dies also gives the can the final set shown in Figures 3 and 4. An annular series of holes 3 are then preferably punched in its lower

end for a purpose to be hereinafter described. 55

The bottom for the can is first formed from a blank 4 of suitable metal, preferably steel, in the shape shown in Figure 5. The middle part of this bottom conforms in shape to that of the bottom of the can 1, but 60 of slightly less size so that it may be firmly fitted within it. Formed on the sides and ends of this bottom part are rectangular flap sections 5 which are adapted to be bent up 90° to form together the side walls of 65 the bottom. Before they are bent up, however, holes 6 are preferably punched in them for registry with the holes 3 in the lower end of the can. Through these registering holes 3 and 6, rivets 7 are adapted to be passed to 70 firmly secure the can bottom 4 within the lower end of the can 1. (See Figure 4.)

Preferably formed on each flap 5 of the bottom 4, and divided therefrom in Figure 5 by a dot and dash line 8, is a flap portion 75 9 whose ends are inwardly cut at an angle of 45° so that when the flaps 5 are bent up to form the side walls of the bottom, these flaps 9 may be folded over an additional 90° to form together the attaching frame unit 80 shown in full lines in said figure. Before the flaps 9 are turned over, however, holes 10, which receive suitable attaching elements, are preferably formed in them at a greater distance apart than the holes 6 in the flaps 5. 85

After the bottom just described is riveted to the lower part of the can 1, solder is poured in the joints between the walls 5 of the bottom and the inner surface of the wall of the can to make them liquid tight. 90

It is thus seen that under our improved method an efficient metal can may be economically manufactured for ice-can and like purposes.

We do not wish to be limited to the details of construction and arrangement herein shown and described, and any changes or modifications may be made therein within the scope of the subjoined claims. 95

Having described our invention, we 100 claim:

1. The herein described method of making metal cans, which consists, first, in rolling a strip of metal into substantially cylindrical form, then welding it along its free longitudinal edges, then expanding it into substantially the desired form, then coating it against the action of air, moisture and 105

chemicals, and then expanding it to a final set.

2. The herein described method of making metal cans, which consists, first, in rolling a strip of metal into substantially cylindrical form, then welding it along its free longitudinal edges, then expanding it from the inside into substantially the desired form, then

coating it against the action of air, moisture and chemicals, and then internally expanding it to a final set. 10

In witness whereof we have hereunto set our hands this 18 day of December, 1924.

RALPH E. BLACKFORD.
CHARLES BUTTERFIELD.
